ATTORNEYS

UNITED STATES PATENT OFFICE.

JOHN ROBERT STONEY, OF OUACHITA, LOUISIANA.

REFLECTOR.

Application filed January 9, 1925. Serial No. 1,460.

To all whom it may concern:

Be it known that I, JOHN ROBERT STONEY, a citizen of the United States, and a resident of Ouachita, in the parish of Union 5 and State of Louisiana, have invented certain new and useful Improvements in Reflectors, of which the following is a specification.

This invention relates to headlights and 10 has for its object the provision of a movable shield adapted to be employed in connection with a lamp for modifying the effect of the light rays whereby glare is eliminated at the will of the operator.

15 A further object of the invention is the provision of a shield movably mounted adjacent a lamp in the headlight which is adapted to be operated electrically and at the will of the driver of the machine.

20 This invention will be best understood from a consideration of the following detailed description, in view of the accompanying drawing forming a part of the specification; nevertheless it is to be understood 25 that the invention is not confined to the disclosure, being susceptible of such changes and modifications which shall define no material departure from the salient features of the invention as expressed in the 30 appended claims.

In the drawings:

Figure 1 is a vertical section of the headlight showing my invention applied thereto.

35 Figure 2 is a rear view in elevation of the operating means for the movable shield.

Figure 3 is a fragmentary enlarged detail of an element of the operating means of the shield.

40 Figure 4 is a view in perspective of the shield.

Referring more particularly to the drawings, 1 designates a parabolic shell forming the reflector of the headlight. Located 45 along the axis of the reflector is a lamp 2 removably mounted in the socket 3 formed at the rear of the reflector 1. The shell or reflector 1 is provided with a slot 4 in which is movably mounted a block 5 secured upon an arm 6 of a movable shield 7. This 50 shield in its operative position as shown in Figure 1 is adapted to be located directly above the lamp 2 with a triangularly shaped lip 8 disposed within the direct rays of the lamp and along the axis of the parabolic mirror. The shield is curved as shown more particularly in Figure 4 and

its rearwardly projecting arm 6 is pivoted as shown at 9 to a bracket 10 secured to the rear wall of the shell 1.

The block 5 which is connected with the shield 7 and movable through the slot 4 in the reflector 1 is provided with a longitudinal bore shown at 11 into which is partially projected a conically shaped roller bearing 12 adapted to engage the flat side 13 of a 60 conically shaped cam member 14 which is movable into the bore 11 but has its longitudinal axis located at one side of the center of the bore so that as the cone-shaped member is moved through the bore 11 it 65 will engage the roller 12 and force the block 5 outwardly and raise the shield 7.

The base of the conical member is cylindrical as shown at 15 and provided with a concaved groove 16 adapted to be engaged 75 by a ball 17 forced outwardly by a spring 18. The spring is maintained in place by a threaded plug 19 screwed into the opening of a passage 20 in which the ball and springs are mounted. The inner opening of 80 the passage 20 is of such a diameter that the ball 17 will be prevented from being discharged from said passage.

A pair of solenoids 21 and 22 are secured by means of brackets 23 to the back of the 85 casing 1 and are electrically connected to a source of current on the automobile for moving the armature 24 back and forth depending upon whether the electrical circuit has been closed to the solenoid 21 or to the 90 solenoid 22. The armatures are slidable in a core running longitudinally and centrally of the solenoids 21 and 22.

The operation of my device is as follows:

When it is desired to modify the rays of 95 light from the headlight to eliminate glare a switch is closed to place the solenoid 21 in circuit and the armature 24 is moved into said solenoid whereby the cone-shaped member 14 is withdrawn from the passage 11 in the block 5 and permitting the shield 7 to drop into the position shown in Figure 1. The switch is then open whence the shield will remain in place. When it is desired to return the shield 7 into engagement with the inner wall of the reflector 1 the circuit to the solenoid 22 is closed thereby energizing the same and causing the armature 24 to be moved into said solenoid and forcing the cone-shaped member 14 into the passage 100 11 so that as the flat side 13 of said member rides against the roller 12 the block 5 105 110 115

will be moved outwardly raising said shield and the cylindrical member 15 is moved to a position where the spring pressed ball 17 will engage the groove 16 and lock the shield in place to prevent rattling of the same. The current to solenoid 22 is cut off. When the solenoid 21 is energized the cone-shaped member will be returned to the position shown in Figure 2 and permit the shield to fall so that the undesirable rays of the headlight will be cut off not only by the shield per se but by the triangular projection 8.

What I claim is:

1. A headlight comprising a casing, provided with a slot, a shield provided with an arm projecting through the slot pivotally mounted on the back of the casing, a block secured to the arm movable through the slot and provided with a central passage, a pair of spaced solenoids, and a single armature movable in the solenoid, a cone-shaped member on the armature and adapted to be moved into the passage in the block and located eccentrically of the passage in the block, said cone-shaped member when moved into the passage in the block engaging the walls of said passage and causing the block to be elevated and likewise the shield.
2. A headlight comprising a casing provided with a slot, a shield provided with an arm projecting through the slot pivotally mounted on the back of the casing, a block secured to the arm movable through the slot and provided with a central passage, a pair of spaced solenoids, and a single armature movable in the solenoid, a cone-shaped member on the armature and adapted to be moved into the passage in the block, said cone-shaped member when moved into the passage in the block engaging the walls of said passage and causing the block to be elevated and likewise the shield and located eccentrically of the passage in the block, said cone-shaped member being provided with a groove, and means in the block en-

gageable with the groove for locking the cone-shaped member in a predetermined position.

3. A headlight comprising a casing provided with a slot, a shield provided with an arm projecting through the slot pivotally mounted on the back of the casing, a block secured to the arm movable through the slot and provided with a central passage, a pair of spaced solenoids, and a single armature movable in the solenoid, a cone-shaped member on the armature and adapted to be moved into the passage in the block and located eccentrically of the passage in the block, said cone-shaped member having a flat side, and a roller mounted in the block and projecting into the passage adapted to engage the flat side of the cone-shaped member.

4. A headlight comprising a casing, a bracket on said casing, a shield pivoted to the bracket, a block having a transverse passage secured to the shield, a cone-shaped member movable in the passage, means for moving the cone-shaped member in opposite directions in the passage, the inclined sides of the cone-shaped member being adapted to engage the walls of the passage when the cone-shaped member is longitudinally moved in the passage for causing the block to be elevated and likewise the shield.

5. A headlight comprising a casing having a slot, a bracket on said casing, a shield having an arm extending through the slot pivotally connected with the bracket, said block being provided with a central passage, a rod mounted eccentrically and longitudinally of the passage in the block, a cone-shaped member on the rod adapted to be moved into the passage in the block and located eccentrically of the passage in the block and when engaged by the walls of the passage said block will be elevated and thereby elevate the shield.

JOHN ROBERT STONEY.
